UNITED STATES PATENT OFFICE

OTTO C. KUEBLER, OF YONKERS, NEW YORK

WATER HEATER

Application filed May 5, 1927. Serial No. 189,115.

The invention relates to means for heating water for domestic use, utilizing heat generated by the house heating boiler and connected up with one of the circulating pipes 5 of the same, and has for its object the provision of means for heating water to the exclusion of the use of a coil within the furnace that has proved to be unsatisfactory because likely to extinguish the fire in the furnace, 10 and also the provision of a heater that is efficient in operation and does not require the use of copper water coil such as is usually found in water heaters.

Another object of the invention is the provision of a water heater of the type referred to, so constructed that the water enters at the bottom and proceeds in a vertical direction upwardly to a discharge port without the intervention of a coil or other obstructing 20 means.

Another object of the invention is the provision of a water heater that is made up of a minimum number of parts and for that reason is reasonable in cost of construction, and 25 extremely efficient in operation, and easily installed.

The invention will be described in detail hereinafter and will be found illustrated in the accompanying drawings in which

30 Figure 1 is a view of a house water heating boiler showing the improved water heater installed in connection therewith and connected up with a conventional domestic hot water supply system,

35 Figure 2 is a similar view showing the water heater installed connected with a vapor or steam heating plant for the purpose of illustration,

Figure 3 is a plan view of the improved 40 water heater,

Figure 4 is a vertical sectional view on a plane indicated by the line 4—4 of Figure 3, and

45 Figure 5 is a transverse sectional view on a plane indicated by the line 5—5 of Figure 4.

In the drawings similar reference characters will be used to designate corresponding parts throughout the several views.

50 Referring to the detailed Figures 3, 4, and 5 of the drawings, the water heater comprises

a casing 1 having top and bottom members 2 and 3 respectively, and a circumferential wall 4 connecting said top and bottom members. The interior of the casing is divided into two chambers 5 and 6 by means of an inner wall connecting the top and bottom members 2 and 3, said inner wall being designated generally 7, and having radial portions 7^a, portions 8 arranged adjacent to the wall 4, and other portions 9 arranged remote from the wall 4 forming recesses 10. The top and bottom members 2 and 3 are provided with threaded nipples 11 and 12 respectively, communicating with the chamber 6 to admit of a heating medium circulating through said chamber by the instrumentalities to be hereinafter described. Wall 4 is provided with an internally extending boss 13 having a threaded opening 14 to which may be connected the water pipe as will be hereinafter more fully described, and said wall is also provided with outwardly extending bosses 15 arranged opposite the indentations 10, and provided with threaded openings 16 to which may be secured a water circulating pipe more fully described herein- 55 after.

The openings 16 also provide means for removing sand cores in casting the article, a plurality of openings being necessary for this purpose because of the indentations 9 in the wall 7 forming the recesses 10, it being also apparent that the openings 11 and 12 and 14 are used for removing sand cores 60 from the molded article.

The bosses 13 and 15 besides utility in strengthening the connections for the pipes from the water storage tank have additional utility in holding the article. The outwardly extending bosses 15 serve to relieve the mold 65 of gases and also to hold the outside core in place, this core being made in two pieces and secured together and suspended in the mold by the three impressions for the bosses. The boss 13 has to be extended inwardly of the circumferential wall of the casing as otherwise the pattern after molding could not be withdrawn from the mold, as this boss is in the drag of the pattern.

70 In the installation of the water heater 100

shown in Figure 1 a water heating boiler is suggested at A having the usual return pipes B; and the heating pipes C leading to the radiators of the house, the water heater being 5 as shown at D installed in one of the heating pipes C as close to the house heating boiler as possible, and connected by means of pipes E and F with the domestic water storage tank G, H indicating an auxiliary heater for summer use.

In Figure 2 the water heater, again designated D, is shown applied to a steam or vapor house heating boiler suggested at I in which J is the return pipe, and K the steam main 15 leading to the radiators, the water heater D being mounted as shown and having its upper end connected just below the water line R in the upper portion of the house heating boiler by means of a pipe L and M designates the return pipe from the generator. N and O indicate pipes leading from the tank P connected to the heater D to convey the cold water from the tank P to the heater and return the water heated to the tank P adjacent 20 to its upper end, manual coal fired water heater being indicated at Q and used as a means for heating the domestic water in the summer when the boiler is not in operation.

It will be understood that as the water 30 heater D in both Figures 1 and 2 is supplied with the hottest of the water; in Figure 1 as it leaves the house heating boiler, and in Figure 2, the connection for the entrance of hot water is about three inches below the water 35 level of the steam or vapor heating plant, a very efficient heating of the domestic water will be accomplished.

The heater is preferably made of some non-corrodible metal such as brass, but for economical reasons can be made of cast iron 40 throughout. Owing to its adaptability to large or small buildings the sizes, form, inlets and outlets may vary without departing from my invention or the scope of the appended 45 claims.

It will also be apparent that my device lends itself to use in connection with utilizing the exhaust of industrial steam engines for heating domestic water or boiler feed water. 50 Also that the heater may be used for heating oil for oil burning heating plants.

What is claimed is:

1. A water heater for domestic heating plants, comprising a casing having top and bottom members and a circumferential wall connecting said members, the space within said circumferential side wall being divided into inner and outer chambers by a continuous inner wall connecting said top and bottom members, said inner wall having inwardly extending recesses, means for connecting the top and bottom members to a source of heating medium for circulation through the inner chamber, a plurality of outwardly extended bosses on the circumferential wall adjacent

one end thereof and having openings therethrough to the interior of the casing, and a single boss extended inwardly of the circumferential wall at the opposite end thereof and having an opening therethrough to the interior of the casing, said openings in the bosses being threaded for connection with a water storage receptacle for circulation of water within the outer chamber to be heated by contact with the wall of the inner chamber.

2. A liquid heater for boilers comprising a casing, a continuous partition in said casing and having portions arranged radially of the space enclosed thereby and connecting portions arranged substantially concentric with the casing, said partition dividing the casing into inner and outer chambers, the outer chamber having means to connect it with a storage tank, and the inner chamber providing a duct for circulation of a heating medium therethrough, said radial portions of the partition and the concentric connecting portions providing a large heating surface and forming recesses communicating with the inner and outer chambers to retard the heating medium and the material therein respectively, and means to convey the heating medium to the inner chamber and to discharge it therefrom.

In testimony whereof I affix my signature. OTTO C. KUEBLER.
